H. C. HARRAGIN.
BRAKE BEAM HANGER.
APPLICATION FILED JULY 6, 1915.

1,170,749.

Patented Feb. 8, 1916.

UNITED STATES PATENT OFFICE

HUGH C. HARRAGIN, OF MONTREAL, QUEBEC, CANADA.

BRAKE-BEAM HANGER.

1,170,749.

Specification of Letters Patent. Patented Feb. 8, 1916.

Application filed July 6, 1915. Serial No. 38,296.

To all whom it may concern:

Be it known that I, HUGH CLYDE HARRAGIN, a subject of the King of Great Britain, and resident of the city of Montreal, Province of Quebec, Canada, have invented certain new and useful Improvements in Brake-Beam Hangers; and I do hereby declare that the following is a full, clear, and exact description of the same.

This invention relates to a brake-beam hanger and appertains particularly to the means of attaching same to the car.

The object of the invention is to provide a brake-beam hanger bracket with a slot having a distorted opening leading thereto for the insertion of the hanger. For full comprehension, however, of my invention reference should be had to the accompanying drawings forming a part of this specification in which similar reference characters indicate the same parts and wherein:

Figure 1 is a perspective view of a portion of a truck and illustrating my improved brake-beam hanger bracket; and Figs. 2 and 3 are face views illustrating the mode of applying the hanger to the bracket. Fig. 4 is an end view of the brake beam bracket.

In the drawings a portion of a wheel truck is shown and includes one of the upright column castings 3 which are located at the sides of the truck and between the wheels 4, being bolted or otherwise suitably secured at top and bottom to the side frame bars 5 of the truck.

The brake shoes are indicated at 6, the beams at 7 and the hangers at 8 and as usual each of the column castings has a bracket extension 9 thereon near the top and which is formed for the attachment thereto of a hanger 8, it being to this connection between the bracket 9 and hanger that my invention specifically applies. The bracket arm is preferably cast in one with the column and extends in the form of a web 9 inwardly therefrom transversely of the adjacent wheel, the web being formed at the end thereof with an enlargement or hub 10 having a longitudinal opening therethrough, the hub and opening being disposed substantially parallel to the axle and the web 9 extending only from the top and far side of the hub with respect to the adjacent wheel, to provide a space between the inner side of the column and opposing end of the hub 10.

The brake beam is suspended from the

lower end of hanger 8, the upper end of the latter being accommodated in opening 11 and supported by the bracket arm and while different arrangements have been employed to retain the hanger in the opening, such have presented the difficulty of necessitating the use of separate retaining means such as nuts, pins and the like and to avoid the resultant disadvantages I have constructed the opening 11 in the form of an open slot in the near or that side of the hub facing the adjacent wheel, such slot being outwardly flared and slightly upwardly inclined and the lips of same having interdigitating lugs 12 formed thereon, such lugs being spaced longitudinally of opening 11 and those of one lip spaced outwardly from the opposite lip so that a distorted mouth leading to the opening is presented, the spacing preferably being such that the mouth is but slightly larger than the thickness of the hanger material.

The hanger I prefer to employ is of rectangular shape and closed or for all practicable purposes endless and in applying same to the bracket it is inserted sidewise until obstructed by one of the lugs 12 and then, following the distorted mouth, turned away from such obstructing lug and moved farther inward and in this manner threaded past the lugs (Figs. 2 and 3) and positioned in opening 11 with its sides at the ends of the hub 10.

When the brake device is assembled the downwardly extending position of the hanger prevents accidental movement of same to an extent sufficient to cause the latter to move through the distorted slot while lugs 12 positively prevent a forward disengagement of the hanger from the bracket and in order to increase the obstruction presented by said lugs the inner faces of those upon each of the lips are inclined in opposite directions toward those of the other lip, that is to say the inner surfaces of the lugs at opposite sides of the opening 11 converge outwardly from the latter to present wedging surfaces restricting outward movement of the positioned hanger and thus obviating excessive shaking of same.

What I claim is as follows:

1. In a car, a truck, a brake beam, a brake beam hanger and a bracket presenting an opening for the reception of the hanger, such opening having a distorted slot leading thereto through which the hanger is inserted.

2. In a car, a truck, a brake beam, a brake beam hanger, a bracket presenting an opening for the reception of the hanger, such opening having a slot leading thereto and spaced lugs upon the lips of the slot.
3. In a car, a truck, a brake beam, a brake beam hanger, a bracket presenting an opening for the reception of the hanger, such opening having a slot leading thereto, and 10 spaced, interdigitating lugs upon the lips of the slot.
4. In a car, a truck including a column casting, a brake beam, a brake beam hanger and a bracket arm upon the casting and 15 presenting an opening for the reception of the hanger, such opening having a distorted slot leading thereto through which the hanger is inserted.
5. In a car, a truck including a column casting, a brake beam, a brake beam hanger, 20 a bracket arm formed with and extending inwardly from the casting, a hub formed at the end of the arm, such hub having an opening formed therethrough for the reception of the brake beam hanger and presenting a slot leading to such opening and spaced and interdigitating lugs upon the lips of said slot forming a distorted mouth through which the hanger is inserted.

In testimony whereof, I have signed my name to this specification, in the presence of two subscribing witnesses.

HUGH C. HARRAGIN.
